COMBINED DISPENSER CAN AND SHAVING BRUSH

Curtis L. Byford, 1084 Siskiyou Ave., Oroville, Calif.

Filed Jan. 21, 1963, Ser. No. 73,249

Term of patent 14 years

(Cl. D9—2)

FIG. 1 is a side elevation view of a combined dispenser can and shaving brush showing my new design;
FIG. 2 is a top plan view; and
FIG. 3 is a bottom plan view thereof.
I claim:
The ornamental design for a combined dispenser can and shaving brush, as shown.
